(57) **CLAIM**

I claim the ornamental design for a fluid filler, as shown and as described.

DESCRIPTION

FIG. 1 is a perspective view of the fluid filler.

FIG. 2 is the front view of the fluid filler.

FIG. 3 is a back view of the fluid filler.

FIG. 4 is a side view of the fluid filler.

FIG. 5 is the other side view of the fluid filler.

FIG. 6 is a top view of the fluid filler.

FIG. 7 is bottom view of the fluid filler.

FIG. 8 is a perspective view of the fluid filler showing the inner handle raised up to open the lid of the fluid container.

FIG. 9 is a perspective view of the fluid filler showing the inner handle raised up to allow water to flow into the fluid container; and,

FIG. 10 is a perspective view of the fluid filler showing the inner handle released and therein closing the lid to the fluid container.

The pool and water are shown in broken lines for illustrative purposes only and do not form part of the claimed design.
